[57] CLAIM

The ornamental a pendant, as shown and described.

DESCRIPTION

FIG. 1 is a perspective view of a pendant showing my new design;

FIG. 2 is a top plan view;

FIG. 3 is a front elevational view;

FIG. 4 is a side elevational view;

FIG. 5 is a rear elevational view;

FIG. 6 is a bottom plan view;

FIG. 7 is a perspective view of a pendant showing a second embodiment of my new design;

FIG. 8 is a rear elevational view of the second embodiment;

FIG. 9 is a bottom plan view of the second embodiment;

FIG. 10 is a perspective view of a pendant showing a third embodiment of my new design;

FIG. 11 is a rear elevational view of the third embodiment; and,

FIG. 12 is a bottom plan view of the third embodiment.

The broken line showing of a partial tether in FIGS. 1, 7 and 10 is for illustrative purposes only and forms no part of the claimed design.
